UNITED STATES PATENT OFFICE.

CLARK ROBINSON, OF EAU CLAIRE, WISCONSIN.

EXTENSION-TABLE.

SPECIFICATION forming part of Letters Patent No. 270,128, dated January 2, 1883.

Application filed July 28, 1881. (Model.)

To all whom it may concern:

Be it known that I, CLARK ROBINSON, of Eau Claire, in the county of Eau Claire, and in the State of Wisconsin, have invented certain new and useful Improvements in Extension-Tables; and I do hereby declare that the following is a full, clear, and exact description thereof, reference being had to the accompanying drawings, making a part of this specification, 10 in which—

Figure 1 is a perspective view of my table closed together. Fig. 2 is a like view of one end of the same extended, the supplemental leaves being in position for raising to engagement with the top. Fig. 3 is a perspective view of the same after said supplemental leaves have been placed in position. Fig. 4 is a central longitudinal section of the table as shown in Fig. 1. Fig. 5 is a like view of the 15 same arranged as seen in Fig. 2. Fig. 6 is a longitudinal section of said table as shown in Fig. 3. Fig. 7 is a cross-section upon line α of Fig. 4 and Figs. 8 and 9 are perspective views of the lower side of said table, and show 20 respectively the relative positions of parts when the same is closed together and when extended.

Letters of like name and kind refer to like parts in each of the figures.

30 The present invention relates to that class of extension-tables in which movable leaves are connected with rails sliding in ways of a stationary table-section, so that by raising said leaves to the level of the top or leaf carried by 35 said stationary section the extension of the table is effected, provision being also made for depressing the leaves and sliding them under the stationary table-top.

The invention consists in a stationary table-40 section having side rails provided with two sets of parallel grooves, in which are fitted bars or slides adapted to move in opposite directions from the center of said stationary table-section, and carrying movable leaves 45 connected with the bars or slides by pivoted links. The inner ends of the bars or slides are cut away or reduced in height, so that when the table is contracted said bars will overlap each other, and thus permit the leaves 50 carried by said bars to lie close together beneath the stationary table-top.

In the annexed drawings, A and A' repre-

sent two side rails which are arranged in parallel lines, and are connected together at their ends by means of two cross-bars, B, and are supported by means of four legs, C, that are secured at the points of intersection of said parts, the whole forming the frame of a table.

The frame thus constructed furnishes support for a top, D, which extends nearly to each 60 end, and has such width as to give the usual projection of its edges over the sides of said frame.

Said top is raised above said frame a distance slightly greater than its thickness, and is sustained in such position by means of 65 a number of metal bars, E, which at suitable intervals are attached to and extend between the lower side of said top and the outer face of each rail A, and from the latter are extended outward, upward, and then inward in straight 70 lines, as shown in Figs. 1, 2, 3, and 7, so as to leave between said top and the upper edges of said side rails, A, a space corresponding to the thickness and width of said top D.

Within the inner face of each side rail, A, are provided two parallel longitudinal grooves, a, which 75 grooves extend the entire length of said rail, and each receives a correspondingly-shaped tongue, f, that is attached to the side and forms part of a slide, F.

The slides F are arranged 80 in pairs, which are connected together at their inner and outer ends by means of two cross-bars, G and H, respectively, and upon the latter is secured a supporting-leg, I, which corresponds in shape and length to the like features of the legs C.

The slides F have equal vertical dimensions, and those at one end have their tongues f arranged near their upper edges for engagement with the upper grooves a, while the opposite slides have their tongues f 85 near their lower edges for engagement with the lower of said grooves a, and each is capable of being moved longitudinally in said grooves.

The inner portions of the slides F are cut away or reduced in height, as is fully 90 shown in Figs. 8 and 9, so that when the table is contracted, or the slides are pushed under the stationary top, said reduced portions, located respectively at the top and bottom of the slides, will pass each other or glide one 100 upon the other, and thus form a lap-joint between the two slides.

Upon the upper edge of the cross-bar H at each end is secured a leaf, I', which corresponds

in position to and when closed inward, as shown in Figs. 1 and 4, forms a continuation of the top D, the abutting edges of said parts being rabbed to make the engagement more perfect. 5 When the sliding ends of the table are drawn outward the space between the top D and leaf I' at each end is filled by means of one or more supplemental leaves, K, which are fitted to and form continuations of said parts, as shown by 10 Figs. 3 and 6.

In order that the leaves K may be connected with the table and readily moved into or from position, each leaf has secured upon its lower face a cross-bar, k, which corresponds in position to the slide F immediately below, and upon the inner face of said cross-bar and slide are pivoted two bars, L, that have such length as to cause them, when arranged vertically, as seen in Fig. 6, to hold said leaf in the exact 15 position necessary for engagement with the leaf I' and top D, from which position said leaf K, by a lateral and inward movement, may be changed to that shown in Fig. 5, its lower face resting upon said slides, and its upper face 20 below the line of the lower face of said top D, in which latter position said supplemental leaf offers no resistance to the inward closing of the sliding end of the table, and when the latter is closed is contained within the space between 25 the said top and the upper edges of the rails A, as seen in Figs. 1 and 4. As thus arranged, it will be seen that the supplemental leaves are easily and quickly moved into or 30

from position, that they are not liable to derangement or displacement, and that when not 35 in use they occupy no space that would be available for other purposes.

It will be manifest that by connecting movable leaves with lap-joint slides as herein shown said leaves, when stowed under the 40 table-top, are permitted to lie close together, thus taking up less space than if the meeting ends of the rails abut together, and enabling a larger number of movable leaves to be used with a stationary table-top of a given area. 45

Having thus fully set forth the nature and merits of my invention, what I claim as new is—

In an extension-table, the combination of the stationary middle section having side 50 rails provided with top and bottom grooves, slides or bars moving in the grooves of the said rails and having overlapping or reduced end portions, the vertically-adjustable leaves, and the pivoted links for connecting the same 55 with the slides, with the table-top supported above the side rails, the end connecting-bars, and supporting -legs of the various sections, as and for the purpose set forth.

In testimony that I claim the foregoing I 60 have hereunto set my hand this 22d day of July, 1881.

CLARK ROBINSON.
